UNITED STATES PATENT OFFICE.

VIRGIL V. LOOMIS, OF PITTSBURGH, PENNSYLVANIA, ASSIGNOR TO UNITED STATES GLASS COMPANY, OF PITTSBURGH, PENNSYLVANIA, A CORPORATION OF PENNSYLVANIA.

DESIGN FOR A GOBLET.

Application filed August 26, 1926. Serial No. 18,882. Term of patent 14 years.

To all whom it may concern:

Be it known that I, VIRGIL V. LOOMIS, a citizen of the United States, residing at Pittsburgh, in the county of Allegheny and State of Pennsylvania, have invented a new, original, and ornamental Design for a Goblet, of which the following is a specification, reference being had to the accompanying drawing, forming part thereof.

Figure 1 is an elevation of a goblet having the foot shown in solid lines and the remainder of the goblet in dotted lines, and

Figure 2 is a view looking down on the

foot of the goblet, the remainder of it being removed.

While the drawing shows a complete goblet, with all except the foot illustrated in dotted lines, the dominant feature of the design is the particular form of foot, as emphasized in the solid line showing.

I claim:

The ornamental design for a goblet, substantially as shown and described.

In testimony whereof I have hereunto set my hand.

VIRGIL V. LOOMIS.
